GAS GENERATOR

Filed Sept. 26, 1929

INVENTOR
WILLIAM MINRATH
A. (W. Deller).
ATTORNEY

UNITED STATES PATENT OFFICE

WILLIAM MINRATH, OF NEW YORK, N. Y.

GAS GENERATOR

Application filed September 26, 1929. Serial No. 395,254.

The present invention relates to gas generators, and more particularly to gas generators of the type wherein the generation of gas is effected by the reaction of a solid material with a liquid usually of a corrosive character.

In the generation of gases, such as hydrogen sulfide, carbon dioxide or the like, a solid material (e. g. iron sulfide, calcium, carbon-
10 ate, etc.) was placed in a gas chamber and an acid aqueous solution, for instance hydrochloric or sulfuric, was placed in a communicating chamber. As the gas pressure decreased in the gas chamber, acid flowed there-
15 in from the communicating chamber and reacted with the solid material to cause the generation of more gas and more pressure. When the gas pressure increased high enough, the acid was forced out of the gas chamber and out of contact with the solid material. The acid thus surged back and forth from the communicating chamber to the gas chamber during the operation of the generator. The aforesaid action required
20 an apparatus capable of resisting the corrosion of acid, of withstanding gas pressure without leaking, and a holding the charge of solid material and acid in separate but communicating chambers. Various types of
25 devices have been proposed for gas generators of the character hereinabove described. Of these generators, the more important were the glass type and the earthenware-glass type. The glass generator was objectionable
30 because it was costly, difficult to make, easily knocked over and broken; cumbersome to charge and refill with fresh materials, awk-
35 ward to clean and limited in size. The more serious objections to the earthenware genera-
40 tor were the complicated structure and num-
ber of parts used, the necessity of disman-
tling practically the entire generator every
45 time it was re-charged, the use of a clumsy
gas outlet pipe having a gooseneck at the
50 end thereof, the difficulty of removing and re-
placing the said clumsy pipe with each
charging operation, the necessity of lifting
the holder for the charge by a handle wetted
55 with acid and the limitation of the size due
to the instability of the tall elongated crock.

or container for acid and to the practical difficulties of constructing a charge holder strong enough for large and heavy charges of solid material and of lifting a large holder charged with solid material in and out of the tall crock.

It is an object of the present invention to provide a gas generator which overcomes the aforementioned objections and disadvantages.

Another object is to provide a gas generator which has a simple construction, which has relatively few parts, which is strong and stable, which is economical and easy to make, and which is convenient and easy to use and charge.

A further object is the provision of a gas generator having a permanent, stationary wall or partition separating the gas chamber from the communicating chamber for acid or the like and having a stationary gas chamber for the charge of solid material incorporated integral with the generator.

A still further object is to provide a gas generator which is capable of being constructed of practically any size ranging from relatively small laboratory models to relatively large industrial models.

Other objects and advantages of the invention will become apparent from the following description taken in conjunction with the accompanying drawings, in which:

Fig. 1 is a longitudinal sectional view of a gas generator embodying my invention;

Fig. 2 illustrates a sectional view taken on the line 2-2 of Fig. 1;

Fig. 3 represents a plan view of the gas generator shown in Fig. 1 with the covers removed;

Fig. 4 depicts the perforated grid used in my gas generator; and

Figs. 5 and 6 are fragmentary views of my gas generator showing modified cover clamping devices.

My improved gas generator will be described in conjunction with the generation of hydrogen sulfide for the purposes of illustration, although it is to be understood that the generator is not to be limited thereto.

The reference character 1 designates a container which has a relatively large base and a relatively low height. Partition or wall 2 divides the container into a gas-tight charge and gas chamber 3 and a communicating chamber 4 for acid. The container is preferably made of earthenware but other suitable materials may also be used. For instance, iron silicide or other metallic materials which are capable of resisting the corrosive action of the acid to be used in the generation of gas or the corrosive action of the reactants and of the products of reaction.

In the present embodiment of my invention, the container 1 is illustrated as having a rectangular shape and flat walls. A construction of this type is preferred because of the stability and rigidity of the generator even in the larger sizes. In addition, the generator has a larger capacity than a corresponding oval or round container and can be fabricated of straight elements or parts. These and other advantages make the instant type of container highly desirable.

Projecting from the walls 5 of charge chamber 3 are a plurality of supports 6 which are preferably of a cantilever type. Seated upon these supports is a removable grid 7 for supporting a charge of solid material 8 which may be iron sulfide, calcium carbonate or the like depending upon the gas to be generated. The grid is preferably provided with a handle 9 to facilitate lifting the grid in and out of the charge chamber. To permit passage of a liquid, such as an acid, through the grid, a plurality of perforations or holes 10 are provided on each side of the handle.

Considerably below the supports, a bottom 11 is located which slopes downwardly toward an outlet 12. In this outlet a drain cock 13 or the like is inserted to control the discharge of liquid, sludge, etc. from the container 1. The liquid not only discharges from chamber 3 but also from chamber 4 via a plurality of ports 14. In the present generator the ports are shown as consisting of two rows of round holes located just above bottom 11.

Placed over charge chamber 3 is a cover 15 which is provided with a knob 16 and a gas outlet 17. For conducting the gas from the charge chamber 3, a glass pipe (not shown) or the like is inserted in outlet 17 in a well known manner, as by a rubber stopper provided with a hole. The gas flows through the pipe and is led to the place of consumption.

To insure a gas-tight condition in chamber 3, a gasket 18, such as a ring of rubber, is placed between the rim 19 of the cover 15 and a flange 20 which projects from the flat side walls of container 1. Flange 20 is reinforced with a plurality of webs 21 which are disposed of at intervals about the periph-

ery of the generator. Between adjacent webs, a plurality of metal hand clamps 22 are positioned to clamp the cover tightly on its seat and to squeeze rubber gasket firmly between rim 19 and flange 20. As the clamps are directly effective upon the earthenware it is preferable to employ rubber or similar washers 23 under the clamping heads in order to avoid a metal to earthenware contact. By screwing the clamps closed the charge chamber 3 is made gas-tight. Of course, sealing compounds, such as petroleum jelly, greases, waxes or other materials, can be applied to gasket 18 to further insure a gas-tight joint.

For covering acid or liquid chamber 4, I prefer to employ a cover 24 which has a handle 25, a rim 26 and a projecting shoulder 27. The rim 26 seats upon flange 19 which preferably extends continuously around the entire periphery of the container. The inner side of rim 26 is supported by an inwardly extending flange 28. As no gas pressure is generated in the acid chamber no gaskets or the like are required between cover 24 and the container.

A modified clamping arrangement for cover 15 is illustrated in Fig. 5. In this arrangement cover 15 is seated upon container 1 in the usual way. Gasket 18 is interposed between rim 19 and flange 20. A clamp 50 is slipped about the container and over cover 15 with its clamping heads 51 located directly under flange 20. A pair of thumb screws 52 are capable of tightening the clamp and making a gas-tight joint between cover 15 and the container. Washers 53 are preferably placed between clamping heads 51 and flange 20 and washers 54 between the inner ends of thumb screws 52 and the top of cover 15 in order to avoid a direct metal to earthenware contact. With this arrangement only one large clamping frame is needed instead of a plurality of small clamps. When this modified clamp is used the webs 21 at the very corners of the container are omitted to permit the clamp to be slid under flange 20.

A further modification of the clamping arrangement is shown in Fig. 6. This modification utilizes a plurality of clamping bolts 75 which are disposed of about three sides of cover 15 and which are pivoted on pivots 76. Each clamping bolt is capable of swinging about its pivot in mating slots 78 formed in rim 19 and flange 20. Thumb screw 77 is adapted to draw the cover home upon gasket 18 and to make a gas-tight joint between cover 15 and container 1.

The operation of my improved generator is obvious to one skilled in the art. A charge of iron sulfide, for instance, is placed upon the grid in the charge chamber. Cover 15 is then placed upon gasket 18 which is seated upon flange 20 of container 1. The clamps 22 are thereupon tightened and a gas-tight

joint is made between cover 15 and the container. A valve outlet pipe is inserted and sealed within gas outlet 17. Cock 13 is, of course, closed so as to render the charge chamber fluid tight when liquid covers inlet ports 14.

After the charge chamber has been prepared in readiness, a reacting liquid 30, such as sulfuric acid in diluted condition, is placed in chamber 4. The acid flows through holes 14 and comes into contact with iron sulfide held upon grid 7. When the acid and the sulfide contact with each other they react to form hydrogen sulfide gas which rises to the top of the charge chamber. As the gas accumulates a pressure is built up within the charge chamber which tends to overcome the static head of acid in chamber 4 and to push the acid which is in the bottom of the charge chamber back into chamber 4. When sufficient gas pressure has been reached the acid is forced out of contact with the iron sulfide and no further generation of gas occurs. As the valve in the outlet line in outlet 17 is opened and gas is drawn off for use, the pressure in the charge chamber 3 falls. With a sufficient fall of gas pressure the static head of acid in chamber 4 again forces acid into contact with the sulfide to cause the generation of more gas. This procedure, as is well known, continues with the use of the gas generator.

When the charge of sulfide has been consumed and is no longer capable of generating further amounts of gas, cock 13 is opened to draw off the spent acid from the generator and any sludge accumulated in the bottom of the charge chamber. The valve in the outlet line is preferably opened to a liquid seal or some liquid or material capable of absorbing any residual gas remaining in the charge chamber. After the acid is drawn off, covers 15 and 24 can be removed and grid 7 lifted out of the container. All of the parts can be thoroughly washed with water or some other suitable medium and prepared for re-charging.

In re-charging the apparatus, grid 7 is first replaced and a charge of sulfide, for instance, is put on the top thereof. Cover 15 is next clamped in position and cock 13 is closed. Acid can now be filled into chamber 4. This acid flows through holes 14 and comes into contact with the charge of iron sulfide to generate hydrogen sulfide gas as described hereinabove.

When carbon dioxide gas is to be generated, calcium carbonate is preferably used as the solid charge and hydrochloric acid as the liquid. In the generation of acetylene, calcium carbide is placed in the charge chamber and plain water in the liquid chamber. For the generation of other gases, appropriate materials are to be used.

It is to be observed that although I have

described a specific embodiment of my invention, the invention is not restricted to such particular embodiment. Various modifications in detail and in the arrangement of the parts may be made by those skilled in the art without departing from the invention as defined in the claims. For example, instead of providing a plurality of supports 6 for the grid 7, a continuous ring or shoulder may be cast integral with the inner wall 5 of chamber 3. Then again, cover 24 may be clamped in place like cover 15 and a hole provided in cover 24 through which gas can be pumped to place the liquid or acid under pressure, thus placing the generated gas in the charge chamber under higher pressures than normal. The available gas pressure may also be increased by building chamber 4 higher so that the static head can be increased to obtain the desired pressure. Similarly, other types of covers and clamping and sealing arrangements can be employed. Furthermore, a set of legs can be cast or made upon the bottom grid 7 to replace the set of supports 6 which project from the wall of the charge chamber. Moreover, the generator can be embodied in the form of cylindrical gas generators as well as rectangular generators as herein described.

I claim:

1. A gas generator comprising a container having a rectangular shape, a partition wall dividing said container into a charge chamber and a liquid chamber, a plurality of ports provided in the lower part of said wall, a grid mounted in said charge chamber above the height of said ports, a cover making a gas tight joint with the top of said charge chamber, and a gas outlet provided in the upper part of said charge chamber for withdrawing gas therefrom.

2. A gas generator as set forth in claim 1 which is constituted of a material of an earthenware type.

3. A gas generator comprising a container having a rectangular shape, a partition wall dividing said container into a charge chamber and a liquid chamber, a plurality of ports provided in the lower part of said wall, a grid mounted in said charge chamber above the height of said ports, a cover making a gas tight joint with the top of said charge chamber, a gasket interposed between said cover and container, and a gas outlet provided in the upper part of said charge chamber for withdrawing gas therefrom.

4. A gas generator comprising a container having a rectangular shape, a partition wall dividing said container into a charge chamber and a liquid chamber, a plurality of ports provided in the lower part of said wall, a grid mounted in said charge chamber above the height of said ports, a cover making a gas tight joint with the top of said charge chamber, clamping means to squeeze the cover

firmly against said gasket to produce a gas-tight joint, and a gas outlet provided in the upper part of said charge chamber for withdrawing gas therefrom.

5. A gas generator comprising a container having a rectangular shape, a partition wall dividing said container into a charge chamber and a liquid chamber, a plurality of ports provided in the lower part of said wall, a grid mounted in said charge chamber above the height of said ports, means to support said grid at said height, a cover making a gas-tight joint with the top of said charge chamber, and a gas outlet provided in the upper 10 port of said charge chamber for withdrawing gas therefrom.

6. A gas generator comprising a container having a rectangular shape, a partition wall dividing said container into a charge chamber and a liquid chamber, a plurality of ports provided in the lower part of said wall, a grid mounted in said charge chamber above the height of said ports, a drain cock for emptying said container of fluid material, a cover 20 making a gas-tight joint with the top of said charge chamber, and a gas outlet provided in the upper part of said charge chamber for withdrawing gas therefrom.

7. A gas generator comprising an earthenware container having substantially a rectangular shape, a partition wall extending interiorly of said container to divide it into a charge chamber and a liquid chamber, said charge chamber having a smaller cross section than said liquid chamber, communicating means incorporated in said partition wall for permitting liquid to flow between said chambers, an earthenware grid mounted in the lower part of said charge chamber above said 30 communicating means, means for supporting said grid in the aforesaid position, a flange positioned about the periphery of the top of the container and on top of said partition wall, an earthenware cover having a rim to mate with said flange about the top of the charge chamber, a gasket interposed between said flange and said rim, clamping means for holding said cover against said flange in a gas-tight condition, a gas outlet provided in 40 the said cover, a drain cock located in the lower part of said container, and a cover for the top of the liquid chamber.

8. A gas generator comprising a container, a transverse partition extending from one 55 wall of said container to another and dividing the same into a charge chamber for solid material and a liquid chamber having its top open to the atmosphere, communicating means provided at the lower portion of 60 said wall for providing fluid communication for liquid to flow into said charge chamber and contact with solid material to generate gas and then to flow back into the liquid chamber upon an increase of gas pressure in excess of the static head of the liquid in said

liquid chamber, a grid mounted in said charge chamber above the bottom thereof for supporting a charge of solid material, a removable cover making a gas-tight joint with the top of said charge chamber whereby a gas storage space is provided therein extending higher than the level of liquid in said liquid chamber, and a gas outlet provided in the upper part of said charge chamber for withdrawing gas from said gas storage space. 70

9. A gas generator comprising an earthenware container, a transverse partition extending from one wall of said container to another thereof and from the bottom to the top thereof and being integral therewith, said partition dividing said container into a charge chamber for solid material and a liquid chamber for liquid capable of reacting with said solid material to generate gas, 80

communicating means provided at the lower portion of said wall for providing fluid communication for liquid to flow into said charge chamber and contact with solid material to generate gas and then to flow back into the liquid chamber upon an increase of gas pressure in excess of the static head of the liquid in said liquid chamber, a grid mounted on said charge chamber above the bottom thereof for supporting a charge of solid material, a removable cover making a gas-tight joint with the top of said charge chamber whereby a gas storage space is provided therein extending higher than the level of liquid in said liquid chamber, and a gas outlet provided in the upper part of said charge chamber for withdrawing gas from said gas storage. 90

10. A gas generator comprising a container, a wall dividing said container into a charge chamber for solid material and a liquid chamber for liquid capable of reacting with said solid material to generate gas, communicating means provided at the lower portion of said wall for providing fluid communication for liquid to flow into said charge chamber and contact with said solid material to generate gas and then to flow back into the liquid chamber upon an increase of gas pressure in excess of the static head of the liquid in said liquid chamber, a grid mounted in said charge chamber approximately above the height of said communicating means, a removable cover fitting only over an upper portion of said charge chamber and making a gas-tight joint therewith whereby a gas storage space is provided therein extending higher than the level of liquid in said liquid chamber, and a gas outlet provided in the upper part of said charge chamber for withdrawing gas from said gas storage. 110

In testimony whereof I have hereunto set my hand.

WILLIAM MINRATH.
